CLAIM

The ornamental design for an automobile or replica, as shown and described.

DESCRIPTION

FIG. 1 is a front and right side perspective view of an automobile or replica showing our new design;

FIG. 2 is a rear and right side perspective view thereof;

FIG. 3 is a right side elevational view thereof;

FIG. 4 is a left side elevational view thereof;

FIG. 5 is a rear elevational view thereof;

FIG. 6 is a front elevational view thereof; and,

FIG. 7 is a top plan view thereof.

The ghosted or low contrasted portions encapsulated by dash-dotted broken lines in the drawings illustrate portions of the automobile or replica that form no part of the claimed design.

1 Claim, 7 Drawing Sheets
